(57) **CLAIM**

The ornamental design for a fabric abrading hand tool, as shown and described.

DESCRIPTION

FIG. 1 is a perspective view of a fabric abrading hand tool showing my new design in a closed configuration, the right side being a mirror image thereof;

FIG. 2 is a perspective view of a fabric abrading hand tool showing my new design in a partially-opened configuration, the right side being a mirror image thereof;

FIG. 3 is a perspective view of a fabric abrading hand tool showing my new design in an alternate condition of use, the right side being a mirror image thereof;

FIG. 4 is a three-quarters perspective view of a fabric abrading hand tool showing my new design, in a closed configuration, the left side being a mirror image thereof; and,

FIG. 5 is a perspective view of a fabric abrading hand tool showing my new design in a closed configuration, the left side being a mirror image thereof.

A fabric abrading hand tool is disclosed. The bottom is flat and circular. The body is cylindrical and therefore the sides are mirror images of one another.
